SOUND PICTURE RECORD

Theodore Willard Case, Auburn, N. Y., assignor to
 Case Research Laboratory, Incorporated, Au-
 burn, N. Y., a corporation of New York

Application June 27, 1928, Serial No. 288,676

26 Claims. (Cl. 274—41.6)

This invention relates to certain improvements in sound picture records and is a continuation in part of my application Serial No. 124,724, filed July 24, 1928, now Patent No. 1,896,682, dated 5 February 7, 1933.

In the production of moving picture films it is customary to splice the film together at various points throughout its length to obtain the desired sequence of pictures and for various other 10 reasons, and when the sound record is produced along one edge of the picture, the splice, which is not detrimental to the moving picture, results in a disagreeable click in the sound picture, and the same effect results when a sound picture is 15 produced upon a film independently of a moving picture.

Further, such disagreeable noise or click exists at the beginning or ending of a sound record, i. e. at the opposite ends of a film record, and may 20 exist at various points throughout the sound record upon the film, as a result of momentary blasting of the source of light which is varied to produce the sound record, or may result from other causes at various parts of the sound record.

And the object of this invention is to eliminate the click or any undesirable noise or abrupt transition as, for instance, at the beginning or ending of a sound record which may result in the reproduction of recorded sound from a sound 25 picture on a film by gradually increasing or decreasing the light transmission capacity of a selected section or sections of the sound track portion of the film.

Other objects and advantages relate to the details of the structure and the form and relation of the parts thereof, all as will more fully appear from the following description taken in connection with the accompanying drawings, in which:

Figure 1 illustrates a sound moving picture film having a portion of the sound record adapted for variable light transmission.

Figure 2 is a modification of Figure 1.

Figure 3 shows how the same effect may be obtained as in Figures 1 and 2, with auxiliary means.

Figure 4 is a modification of Figure 3.

Figure 5 illustrates a sound track construction at the beginning and ending of a film.

Figure 6 illustrates the beginning and ending of a positive sound picture record.

Figures 7 and 8 are respectively, modifications of Figures 5 and 6.

Figures 9 to 11 illustrate various means for eliminating undesirable portions of the sound record.

I have here illustrated a sound record as produced at one edge of a moving picture film, but it will be obvious that that is not essential, and the sound record may be produced upon an independent film, if desired. As illustrated in the 5 figures, the frames B in the center of the film B represent the moving picture portion of the film and the narrow strip C at the left of the frames B indicates the sound record portion of the film.

As shown in Figures 1 to 4, the film has been 10 spliced by overlapping the adjacent ends between the full line D and the dotted line E. Under this condition it is found that in reproduction an undesirable click or noise results when the portion of the record at the splice is reproduced, 15 and I have found that this undesirable noise or click can be eliminated by gradually decreasing the light rays passing through the film from a point some distance forward of the splice up to the splice, and then gradually increasing the light 20 rays passing through the film from the splice rearwardly of the film, i. e. gradually decreasing the rays of light passing through the film from a normal condition of the sound record to a condition where substantially no rays pass 25 through the film at the spliced portion between the lines D and E, and then gradually increasing the light rays passing through the film from the line D rearwardly of the film to a point where the film again assumes its normal sound record 30 condition.

In view of the fact that it is usual to utilize a negative for the production of a number of positives, and that the positives are usually utilized for the reproduction of the original sounds, 35 the negative being retained merely for the production of positives, the condition just described of gradually decreasing and gradually increasing the rays of light through a portion of the film to eliminate undesirable noises is produced 40 upon the positive, altho if the negative is itself to be used for sound reproduction, this condition should be produced upon the negative.

In Figures 1, 2, 3 and 4, therefore, the films A may be either a negative or a positive, but as before suggested, a positive is usually utilized in the actual reproduction of talking moving pictures.

In Figure 1 this gradual decrease and gradual increase of the passage of light rays through the 50 film is effected by rendering a tapered portion of the film adjacent the splice and forward of the dotted line E substantially opaque, i. e. at the line E the entire width of the sound record is rendered substantially opaque, and a line border- 55

ing the opaque portion forward of the line E extends from one side of the film record diagonally across the record to the opposite edge thereof thereby producing an opaque strip of tapered form gradually increasing in width up to the splice, at which point it substantially equals the width of the effective portion of the sound record.

The entire portion of the sound record between the lines D and E is rendered opaque and rearwardly of the line D a corresponding gradual increase of the light rays passing through the film is effected by rendering a tapered portion of the sound record opaque, the opaque portion at the line D substantially equaling the width of the film and being bounded by a line extending from one edge of the sound record diagonally to the other edge thereof. In this manner two similar tapered portions F and G are formed leading to and from the splice whereby the passage of light rays through the film is gradually decreased and increased, to thereby eliminate any sudden change which results in the undesirable noises described.

The two tapered substantially opaque portions 25 F and G may be produced in any suitable way, as perhaps by covering the film with a suitable substantially opaque material, as for instance paint.

In Figure 2 substantially the same result is 30 accomplished in a somewhat different manner in that the entire width of the sound record is gradually made less transparent from a point forward of the splice up to the splice, at which point the record is rendered opaque, and then rearwardly 35 of the splice the entire width of the sound record from a condition of opacity is gradually rendered less opaque to a point at which the sound record portion of the film remains in its normal condition, thereby forming two portions upon opposite 40 sides of the splice, the one forward of the splice gradually increasing in opacity or decreasing in transparency from the normal condition of the sound record to an opaque condition at the splice, and then rearwardly of the splice gradually increasing in transparency from a condition of 45 opacity to the normal condition of the sound record.

The treated portion of the sound record forward of the splice is indicated by the letter H and 50 the treated portion of the sound record rearwardly of the splice is indicated by the letter K. Any suitable means for effecting this increase and decrease in transparency may be utilized, as for instance by coloring the film.

In Figure 3 a further structure for effecting 55 the same result is illustrated in that the source of the light rays passing through the sound record is automatically and gradually varied so that the light rays passing through the film are gradually decreased forwardly of the splice and gradually increased rearwardly of the splice by controlling the source of said rays.

This may be accomplished in any suitable manner, as for instance by forming the edge of the 60 film with a recess or concavity M, which gradually increases in depth to a maximum and then gradually decreases in depth until it again intersects the edge of the film. This recess is properly positioned and utilized in connection with 65 the bar N which has its inner end in contact with the edge of the film, and is spring-pressed inwardly as by spring O. This bar N is connected to one end of a lever P, the opposite end of which operates as one of the contacts of a 70 rheostat R included in the circuit containing the

source of potential S which lights the lamp T. The arm N moves inwardly under the action of spring O when the recess M in the edge of the film moves by the end of the arm, and in this manner the rheostat R is automatically controlled so as to gradually decrease and gradually increase the current flowing in the lighting circuit for the lamp and the condition can be readily adjusted so that the lamp will be unlighted or practically unlighted at the splice, this 10 condition being reached by a gradual variation in the rays emanating from the lamp to thereby eliminate the click ordinarily produced by the passage of a splice in the sound record.

In Figure 4 a structure somewhat similar to 15 Figure 3 is disclosed except that the recess or notch in the edge of the film and which actuates the bar N is utilized for controlling a shutter W of any suitable and well known form, to thereby control the passage of light from the source T to 20 the sound record. The recess M in the film is of such form so that in cooperation with the arm N the passage of light to the film may be varied gradually from normal intensity to a condition at which no light passes. Obviously the range of 25 such adjustment may be predetermined within any desired limits.

Figure 5 illustrates this invention as applied 30 at the beginning and ending of a sound record on a film. As the sound record itself as produced upon the film acts to vary the light transmission of the film, undesirable noise exists at the beginning and ending of such a record, due to the sudden change in the value of the light transmission 35 of the film.

In order to avoid this undesirable noise, it is 40 only necessary, as shown in Figure 6, to produce upon the sound record portion of the film which is to be used for reproduction, preferably as stated, the positive film which is illustrated in 45 Figure 6, a substantially opaque portion 1 which may as shown begin at the end of the film and continues up to substantially the point where it is desired to begin reproduction of the sound record. At this point the substantially opaque portion 45 is gradually tapered off, as for instance along a diagonal line until a normal condition of the sound record is reached.

This tapered portion marker 2 should be of 50 sufficient length so as to graduate the light transmission over a sufficient portion of the sound record to prevent the production of the undesirable noise. At the end of the film to be used in reproduction, as for instance the positive, as 55 shown in Figure 6, the reverse condition is produced beginning at a normal condition of the sound record, the light transmission of the film is gradually decreased through a tapered area 3 gradually increasing in width until it occupies 60 the entire area of the sound record, and this opaque portion 4 may be continued to the end of the film, if desired.

In this manner the undesirable noise which 65 ordinarily occurs at the beginning and ending of a sound record is eliminated by the gradual variation in the light transmission of the film adjacent these points. As before stated, the film 70 which is to be used in reproduction is the film which should be treated so as to produce the condition shown in Figure 6, but if that film be the positive, as is usual, the negative from which this positive is produced should be treated in a reverse manner, and such a negative for producing the positive of Figure 6 is shown in Figure 5 75 where the opaque strip marked 1 in Figure 6 is a

substantially transparent strip 5 leading up to a substantially transparent tapered portion 6, and at the end of the film the strip 7 is rendered substantially transparent, or any means may be provided for permitting the substantially free passage of light rays through this portion leading up to the tapered substantially transparent portion 8.

When a positive is printed from such a negative, the transparent portions upon the negative reproduce substantially opaque portions upon the positive, and this is the desired condition when the positive is the film adapted to be used for reproducing the original sound.

The structures shown in Figures 7 and 8 are substantially the same in operation as those shown in Figures 5 and 6, except that instead of showing tapered portions transparent in the negative and opaque in the positive, which extend from one edge of the sound record to the opposite edge, the substantially transparent tapered portions 9 and 10 in the negative of Figure 7 are V-shaped, with their apices at substantially the central portion of the film, and the opaque tapered portions 11 and 12 of the positive shown in Figure 8 are such as to be reproduced by printing of a positive from the negative of Figure 7.

The result, however, in reproduction of the positive of Figure 8 is substantially the same in the elimination of undesirable noise as that disclosed in the previous figures.

The opaque portions desirable upon the positive at any of the points described may be produced, as stated, by rendering corresponding portions of the negative substantially free to the passage of light rays. This may be accomplished in any suitable manner. However, a positive may be printed from a negative, as originally produced, and the positive may then itself be treated in any suitable manner to render the desired portions opaque, as for instance by painting the desired portions with a substantially opaque material, or with ink, or by pasting a properly shaped opaque strip of material over the desired portion, and in Figure 9 there is illustrated a positive having opaque triangular pieces or sheets of opaque material 13 and 14 pasted on the film at the desired points to gradually vary the light transmission of this portion of the film.

In Figure 10 there is shown a sound record upon a film in which undesirable noise would be caused at the point 15 due to the fact that the sound record is defective at this point resultant from blasting of the lamp, or otherwise. This is illustrated as upon the film which is to be used for reproducing the sounds, and may be either the positive or negative. If it be the negative, any suitable means may be utilized for producing an oppositely tapered substantially triangular portion which when printed would produce the substantially opaque truncated cone section 16 upon the positive, or if the positive be directly printed from a negative having an undesirable part 16 then the substantially opaque portion 16 may be produced on the positive in any suitable way, as by painting, inking or pasting a substantially opaque piece of material upon this portion of the positive. In this manner the undesirable portion of the sound record is eliminated and the section is usually so short as not to audibly interrupt the reproduction of the original sounds.

The invention here, therefore, contemplates a means for eliminating undesirable sounds at any

portion of a sound record and this can be effected by rendering the sound record inoperative at selected portions of the film. This inoperativeness of such portions can be accomplished by rendering these portions of the film adapted to be used for reproduction substantially opaque to light transmission, and such a positive can be reproduced from a negative by rendering corresponding portions of the negative substantially transparent to light transmission.

For the purpose of claims of this application, the image on a positive of a splice in the negative or the portion of the positive which underlies the negative and upon which said image would appear after printing, is deemed the equivalent of a splice in that it produces the same undesirable noise and requires exactly the same gradual increase and/or decrease in light transmission capacity to eliminate the undesirable noise.

And although I have shown and described a specific means and structure for accomplishing this result, it will be obvious that various means and apparatus may be utilized, and that the structures may be produced in various ways, all without departing from the spirit of this invention as set forth in the appended claims.

I claim:

1. The combination with a spliced film having a sound record thereon, of means for gradually decreasing light rays passing through the film from a point forward of the splice up to the splice, and means for gradually increasing light rays passing through the film rearwardly of the splice to a normal condition of the sound record.

2. The combination with a spliced film having a sound record thereon, of means for gradually decreasing light rays passing through the film from a point forward of the splice up to a condition where substantially no light rays pass through the film at the splice, and means for gradually increasing light rays passing through the film rearwardly of the splice to a normal condition of the sound record.

3. The combination with a positive having a sound record thereon including the image of the splice in the negative from which the positive was produced, of means for gradually decreasing light rays passing through the positive from a point forward of the image of the splice, and means for gradually increasing light rays passing through the positive rearwardly of the image of the splice to a normal condition of the sound record.

4. The combination with a spliced sound record element having a sound record thereon, of means for gradually decreasing light rays passing through the sound record portion of the element from a point forward of the splice up to the splice.

5. The combination with a spliced sound record element having a sound record thereon, of means for gradually increasing light rays passing through the sound record portion of the element rearwardly of the splice to a normal condition of the sound record.

6. A film adapted to receive a sound record, a sound record on a portion of the film, means preventing the passage of light rays through the portion of the film having no sound record thereon, and means enabling the passage of a gradually increasing number of light rays through the film at approximately the point where a sound record first appears on the film.

7. A film having a sound record thereon, means for gradually decreasing the light transmission

capacity through a portion of the sound record to a point of substantially no transmission capacity, and means adjacent the aforesaid means for gradually increasing the light transmission capacity through another portion of the sound record from a condition of substantially no transmission capacity to normal transmission capacity of the sound record.

8. A film having a sound record thereon, means additional to the sound record for gradually diminishing the light transmission capacity of the sound record at a selected portion thereof, and means additional to the sound record for gradually increasing the light transmission capacity through another selected portion of the sound record.

9. A film having a sound track, a record corresponding to sound waves on said track, and means gradually increasing the light transmission capacity through a selected portion of said sound track.

10. A film having a sound track, a record corresponding to sound waves on said track, and means gradually decreasing the light transmission capacity throughout a selected portion of said sound track.

11. In a positive film printed from a previously spliced negative film and having a sound track and a sound record printed thereon, means for rendering the portion of the positive film corresponding to the spliced portion of the negative film substantially opaque to the passage of light rays and for rendering portions of said positive film at opposite ends of said substantially opaque portion of gradually decreasing light transmission capacity as they extend from the opaque portion toward those portions having normal light transmission capacity of sound record.

12. A film including a sound track portion, a record of light waves corresponding to sound wave variations on said track, means additional to the sound record for gradually decreasing the light transmission capacity through a portion of said sound track.

13. A film including a sound track portion, a record of light waves corresponding to sound wave variations on said track, means additional to the sound record for gradually increasing the light transmission capacity through a portion of said sound track.

14. A film having a sound track portion, a record corresponding to sound waves on said sound track, means additional to the sound record for gradually decreasing the light transmission capacity through a selected portion of the sound track, and means adjacent to the aforesaid means and additional to the sound record for increasing the light transmission capacity through another selected portion of said sound track.

15. A film having a sound track portion, a record corresponding to sound wave variations on said track, means additional to the sound record for gradually decreasing light transmission through a selected portion of the sound track from a normal transmission capacity of the sound record to substantially no transmission capacity, and means additional to the sound record for gradually increasing the light transmission capacity from the point where substantially no transmission takes place, to a normal transmission capacity of the sound record.

16. A film having a sound track portion with a splice in the same, a record corresponding to sound wave variations on said sound track, means additional to the sound record for gradually de-

creasing the light transmission capacity through a selected portion of the sound track forward of the splice up to substantially no transmission capacity at the splice, and means additional to the sound record for gradually increasing the light transmission capacity through a selected portion of the sound track rearwardly of the splice from substantially no transmission capacity at the splice to a normal transmission capacity of the sound record.

17. A film having a sound record thereon, a selected portion of which is covered through its width with an opaque material and adjacent tapering portions on opposite sides of the first-named portion covered with the same material whereby the light transmission of said sound record is gradually changed from normal transmission capacity to substantially no transmission capacity at the selected portion and gradually changed from substantially no transmission capacity to normal transmission capacity rearwardly of the selected portion.

18. A positive film printed from a previously spliced negative film having the portion corresponding to the spliced portion of the negative film substantially opaque to the passage of light rays, and sections on opposite sides of said portion of gradually increasing light transmission capacity as they extend from said portion.

19. A film having a sound record thereon, means for gradually decreasing the amount of light transmitted through a portion of the sound record to a point of substantially no transmission and means for gradually increasing the amount of light transmitted through another portion of the sound record from a condition of substantially no transmission to normal transmission of sound record.

20. A film having a photographically effected area of varying density corresponding to sound wave variations, and a tapered portion of said photographically effected area being rendered substantially opaque.

21. In the art of sound photography, the method of reducing the objectionable sound effect at the changeover from one piece of sound record to another which comprises obscuring part of the sound record at the change-over point by applying a piece of opaque, flexible material.

22. A motion picture film having thereon two consecutive areas containing photographic sound records joined together, and a piece of opaque material applied to the sound record for obscuring a portion of each record at the junction point.

23. A motion picture film having thereon two consecutive areas containing photographic sound records joined together at their ends, and a piece of opaque, flexible material having tapering ends applied to the sound record and serving to obscure a portion of each of said sound records at the junction point.

24. A motion picture film having thereon two consecutive areas containing photographic sound records joined together and a piece of material applied to and obscuring a portion of each record at and adjacent the junction, the total light transmitted by the sound record and the applied piece varying gradually longitudinally of the record.

25. In the art of reproduction of sound from photographic records, the method of reducing objectionable sound effects at the point of change-over from one accompaniment to another on the same continuous record which comprises apply-

ing to the sound record adjacent the point of change-over a layer which progressively increases the density of the record.

26. In the art of reproduction of sound from photographic records, the method of reducing objectionable sound effects at the point of change-over from one accompaniment to another on the same continuous record which comprises

applying to the sound record at the point of change-over a layer which gradually increases the density of the sound record to substantially the point of change-over and then gradually diminishes the density of the record from that point. ⁵

THEODORE WILLARD CASE.
